UNITED STATES PATENT OFFICE

SAMUEL GOLDFINGER, OF NEW YORK, N. Y.

LAMP

Application filed January 16, 1931. Serial No. 509,139.

My present invention relates generally to an illuminating device, and has particular reference to a novel type of lamp.

A general object of my invention is to provide a lamp or lighting arrangement which provides an efficient type of so-called indirect lighting for the room in which the lamp is placed.

Another object of my invention is to provide an arrangement wherein the illumination is not confined to such indirect lighting, but simultaneously provides a relatively small, yet ample, amount of gentle and pleasing illumination in a downward direction, in the more or less conventional manner.

A more particular object of my invention lies in providing a device which has the outward appearance of a lamp of the conventional kind in connection with which indirect illumination is not contemplated or expected.

A still further object of my invention lies in providing an arrangement wherein a single source of light, such as an electric bulb, accomplishes all of the desired objects and wherein I simultaneously achieve the advantages and desirable characteristics of a pure indirect-lighting arrangement, usually of a relatively ugly and unattractive appearance, and the desirable features of a normal type of lamp, which is usually of more pleasing and attractive appearance and which produces a gentle downwardly directed and relatively local illumination.

One of the main features of my invention lies in providing a peculiarly efficient cooperative arrangement of two reflectors, one of which is a main upwardly divergent reflector serving to confine the illumination from the source of light to an upwardly directed beam, and the other of which is an auxiliary and downwardly divergent reflector which functions in a predetermined manner for directing only a certain portion of this beam downwardly for local illumination.

In general, my present invention provides an arrangement which is relatively simple in construction and hence inexpensive to manufacture and easily assembled, and which is not only staunch and efficient but at the same time

devoid of unsightly and relatively complex and cumbersome supports, shades, reflectors, and the like.

I achieve the foregoing objects, and such other objects as may hereinafter appear or be pointed out, in the manner illustratively exemplified in the accompanying drawings, wherein—

Figure 1 is an elevational view of a lamp embodying the features of my present invention;

Figure 2 is an enlarged cross-sectional view of the upper portion of Figure 1; and

Figure 3 is a plan view taken substantially along the line 3—3 of Figure 2, with the outer shade removed.

By way of example, I have illustrated a standing lamp wherein a pedestal 10 is adapted to rest upon a floor 11 and carries a post or stanchion 12 on the upper end of which the lamp proper is mounted.

In accordance with my present invention, I mount a main reflector 13 upon the post 12, this reflector being upwardly concaved or upwardly divergent and being provided with means to accommodate a source of illumination, such as the electric bulb 14. More particularly, I provide a hollow portion 15 on the post 12 within which an electric light socket (not shown) is mounted. The bulb or lamp 14 is adapted to be screwed into this socket from above, and the reflector 13 is so fixed that the bulb will lie in its entirety within the confines of the reflector. A pull-chain or the like 16 may extend from the side of the portion 15 for controlling the operation of the lamp 14.

The reflector 13 is opaque and is adapted to direct all the illumination from the lamp 14 upwardly so as to confine this illumination to an upwardly divergent beam. In the illustrated form, I have shown a preferred way of accomplishing this by the provision of a separate reflecting insert 17. This insert conforms to the contour of its container portion, and the combination of the portions designated by the reference numerals 13 and 17 will hereafter be referred to as a single entity constituting the main reflector of the device.

At its upper edge, this reflector is provided with an outwardly projecting marginal flange 18 which may be said to be substantially horizontal, although in the illustrated embodiment I have shown a very slight upward divergence thereof. The width of this marginal flange is relatively small with respect to the total diameter of the reflector 13. At its outer periphery, I have shown the flange 18 provided with an upwardly directed bead or rim 19 which may be advantageously provided thereon but which is not essential.

The flange 18 is essentially a light-transmitting member, and I have illustratively shown the same as an integral portion of the reflector 13 and provided with a series of apertures or openings 20. The portions between the openings are relatively opaque, and the openings themselves, whether provided with inserts of glass or the like or not, serve as light-transmitting apertures.

In accordance with my invention, I provide a second or auxiliary reflector which is downwardly concaved and which is in the form of an annulus 21. This reflector is opaque and has its under-surface constructed to serve as a reflecting surface. I have illustratively shown the manner in which a separate reflecting member 22 may be arranged along the inner surface, although this particular arrangement is not essential, and the assembly 21—22 will hereinafter be referred to as an entity constituting the auxiliary reflector.

The reflector 21 is mounted directly upon the flange 18, and, more particularly, at the free edge of the latter. By way of example, I have shown the lower free edge of the reflector 21 provided with a bead or rim 23 which is adapted to rest and find support upon the upper edge of the rim 19.

In accordance with my present invention, the auxiliary reflector 21 is an entirely separate element and is capable of removable application into its operative position, resting merely by gravity upon the edge of the flange 18. The removability of the annulus 21 has a great advantage from a manufacturing and assembling standpoint, and also greatly facilitates access to the bulb 14 and access, for polishing or replacement purposes, to the interiors of the reflectors 13 and 21.

The central opening defined by the annulus 21 is of sufficient size to permit most of the upwardly directed beam from the lamp to pass through it, as indicated in a general way by the arrows 24.

The present construction is completed by the provision of an outer shade 25 which is substantially tubular in structure and is adapted to find support, at a midportion thereof, upon the outer surface of the annulus 21. More especially, it is to be noted

that in the illustrated form I have provided a ring 26 upon the interior of the shade 25, which ring is adapted to rest upon the bead or rim 23 to hold the shade 25 in its proper position.

The shade is preferably of a contour which is downwardly divergent, as shown, so that the general appearance of the entire structure is somewhat identical with that of conventional lamp structures. The shade may be said to have a downwardly flaring skirt portion which extends downwardly below the level of the flange 18, and also an upper portion which extends upwardly beyond the level of this flange. It is to be particularly noted that the upper edge 27 of the shade 25 lies above the uppermost surface of the reflector 21, while the lower edge 28 of the shade 25 lies below the reflector 13. In this way, the shade effectually conceals the entire reflector arrangement, and, more particularly, conceals from view the construction of the flange 18 and the arrangement of the auxiliary reflector thereover.

The operation of the device will be obvious from the description given. The main illumination is confined to an upwardly divergent beam which passes freely through the opening in the annulus 21 and provides for the indirect-lighting effect of the lamp as a whole. In other words, this beam upon striking the ceiling, will be reflected downwardly by the ceiling in a diffused manner which may efficiently serve to illuminate an entire room with a gentle, glareless, yet highly efficient, light. The marginal portion of this upwardly directed beam impinges upon the undersurface of the reflector 21, as indicated by the arrows 29, and this reflector is so contoured that these beams will be reflected downwardly in a substantially vertical direction, as indicated by the arrows 30, this downward beam passing through the flange 18 and providing a local, gentle, yet ample illumination of wellknown character.

It will thus be noted that an extremely efficient illumination is provided, none of the light being dissipated, all of the advantages of indirect illumination being achieved, and the desirable features of the conventional type of illumination being retained. It is further to be noted that all these advantageous results are achieved by a single bulb or source of illumination which is efficiently housed in an extremely simple and good-looking structure.

Obviously, many of the structural features herein illustrated may be modified to suit differing requirements. Although I prefer to make the portions 15, 13, 18, and 21 of metal, other materials may be employed, if desired. To achieve the maximum advantages, I have found it most desirable to make the reflectors 13 and 21 opaque. The apertures or openings 20 in the flange 18 may be of any desired con-

tour or configuration and may be provided with inserts of glass, frosted or unfrosted; or the entire flange may, if desired, be constructed of a light-transmitting substance. 5 The annulus 21, though advantageously of a removable character, need not necessarily be provided as a separate element; and the flange 18, though preferably integral with the reflector 13, may, if desired, be constructed in a different manner. The outer shade may have any preferred contour and may be of any suitable material, such as parchment, fabric, or the like, and although I prefer to mount it in the removable manner shown, other arrangements may be resorted to if found preferable.

Obviously, also, the features of my invention are not restricted to a standing lamp of the character illustrated, and table lamps, 20 piano lamps, or other types of lighting fixtures, may readily be constructed to embody the same advantageous novel features. From certain aspects, even the symmetrical, circular construction herein illustrated by way of 25 example need not be adhered to under all conditions.

In general, it will be obvious that changes in the details herein described and illustrated for the purpose of explaining the nature of 30 my invention may be made by those skilled in the art without departing from the spirit and scope of the invention as expressed in the appended claims. It is therefore intended that these details be interpreted as illustrative, and not in a limiting sense.

Having thus described my invention, and illustrated its use, what I claim as new and desire to secure by Letters Patent is:—

1. In a floor lamp of the character described, an upwardly divergent, opaque reflecting bowl, a source of light therein, a substantially horizontal, outwardly projecting flange integrally formed on the upper edge of said bowl and having light-transmitting openings therein, and an upwardly convergent, opaque reflecting annulus removably mounted on the peripheral edge of said flange for directing certain light beams downwardly through said openings.

10 2. In a floor lamp of the character described, an upwardly divergent, opaque reflecting bowl, a source of light therein, an outwardly projecting flange arranged on the upper edge of said bowl and provided with light-transmitting openings therein, an upwardly convergent, opaque reflecting annulus supported on the periphery of said flange to direct said light beams downwardly through said openings, and a substantially 20 tubular shade for the lamp encircling said flange and provided with means upon the interior thereof for resting upon the lower edge portion of said annulus.

3. In a floor lamp of the character described, a pedestal, an upwardly concaved,

opaque reflecting bowl on said pedestal and having a source of light therein, the illumination from said source being thereby confined to an upwardly divergent beam, an outwardly projecting, substantially horizontal flange on the upper edge of said bowl and having some opaque portions and some portions adapted freely to transmit light therethrough, and a downwardly divergent, auxiliary reflector supported on its edge upon the peripheral portion of said flange, said auxiliary reflector having an opening in its midportion adapted to permit passage therethrough of most of said upwardly divergent beam, the marginal portion of said auxiliary reflector serving to direct the marginal portions of said beam downwardly and undif fusedly through said light-transmitting portions of said flange. 70 75 80

4. In a floor lamp of the indirect-lighting variety, a pedestal, an upwardly divergent, opaque reflecting bowl on the upper end of said pedestal, a source of light in said bowl, a substantially horizontal flange projecting outwardly from the upper edge of said bowl 90 and provided with openings therein adapted to permit free passage of light therethrough, an upwardly convergent, opaque reflecting annulus mounted on the outer edge of said flange, and a tubular shade mounted on said annulus and surrounding said bowl and annulus to conceal the latter, whereby the major portion of the light reflected by said bowl will emerge from the upper end of the shade in an upwardly divergent beam adapted to be 100 reflected in diffused condition by the ceiling, while at the same time certain light rays encountering said annulus will be reflected downwardly by the latter through said flange openings and will emerge undiffused from the lower end of the shade in an annular beam surrounding said pedestal. 95 105

In witness whereof I have signed this specification this 12th day of January, 1931.

SAMUEL GOLDFINGER.
